Pierre Barnes

ATTORNEY

UNITED STATES PATENT OFFICE.

GLENN A. MORRELL, OF SEATTLE, WASHINGTON, ASSIGNOR TO ALBERT P. ROBINSON,
OF SEATTLE, WASHINGTON.

FIREPLACE DAMPER.

Application filed March 8, 1924. Serial No. 697,735.

To all whom it may concern:

Be it known that I, GLENN A. MORRELL, a citizen of the United States, residing at Seattle, in the county of King and State of Washington, have invented certain new and useful Improvements in Fireplace Dampers, of which the following is a specification.

This invention relates to fireplace dampers and more particularly to the controlling 10 means therefor.

The object of my invention is the provision of improved devices permitting movement of the damper plate yet acting to normally retain the same in selected intermediate positions.

With these and other ends in view, the invention consists in the novel construction, adaptation and combination of parts herein-after described and claimed.

20 In the accompanying drawings—

Figure 1 is an end view of a fireplace damper embodying my invention; Fig. 2 is a plan view of the same, partly broken away; Fig. 3 is a transverse section on line 3—3 of Fig. 2, but with damper plate shown in a different position; Fig. 4 is a vertical longitudinal section on line 4—4 of Fig. 3.

In said drawing, the reference numeral 5 30 represents, generally, the damper-frame member which is adapted to fit in the throat of a fireplace. Said frame is provided with a throat passage 6 enclosed between front and back walls 7 and 8, and between end 35 walls such as 9. As illustrated, the front wall 7 extends as at 10 below the plane of the other walls to support a lintel element 11.

Said frame walls are desirably arranged 40 to converge upwardly as shown, and the end walls 9 are inclined horizontally to provide a throat passage of less width at the rear than at the front thereof.

The damper plate, represented by 12, is 45 provided adjacent its front edge 13 and near each of its ends with a depending arm such as 14 having a laterally disposed trunnion element 15 which serves as a pivotal support for the damper plate in apertures such as 16 provided in the respective end walls of the frame.

17 represents a handle-arm shown as secured to a trunnion element 15 of the damper plate whereby the latter is adjustably 55 moved into selected positions.

According to the present invention, at one end of the frame I provide a plate 18, hereinafter designated as the bolster, which protrudes above the frame proper and is advantageously formed coextensive with an 60 end wall 9 as shown.

The upper surface 19 of said bolster is of an arcuate shape disposed concentric, or nearly so, with respect to the axis of the apertures into which extend the damper 65 plate trunnions.

The bolster surface 19 serves as a bearing for a stud or protuberance 20 of the damper plate, said stud being located at or adjacent to the rear edge 21 of the damper plate. 70

In practice, the stud 20 and bolster 18 coact with the trunnions and the bearings therefor in the respective end walls of the frame to support the damper plate in different adjusted positions. Furthermore, the 75 frictional engagement of the stud with the bolster surface serves to retain the damper plate against accidental displacement but permit the damper plate being moved through the medium of the handle arm 17. 80

What I claim, is,—

1. In a damper, a damper frame having a bolster element rigid therewith, a damper plate pivotally connected to said frame, and a stud protruding from an end of the 85 damper plate to bear upon said bolster element for sustaining the damper plate at one edge thereof and serving to frictionally resist movement of the damper plate.

2. In a damper, a damper frame, a damper plate pivotally connected adjacent one edge thereof to the damper frame, a stud extending laterally from said damper plate and adjacent to its other edge, and means rigid 90 with said frame and engaged by the stud to support a portion of the weight of said damper plate in its different positions and serving to frictionally resist movement of the damper plate. 95

3. In a damper, the combination with a damper frame, of a bolster element extending upwardly from an end of the frame, a damper plate movably connected to said frame and means carried by the damper plate and engaging the upper surface of said bolster element for retaining the damper plate in selective adjusted positions with respect to the frame. 100

4. In a damper, a damper frame, a bolster at one end thereof, a damper plate movably 110

mounted in said frame, means carried by the damper plate and engaging with the upper surface of the bolster for supporting a portion of the weight of the damper plate, and 5 operating means for overcoming the frictional resistance of the first named means with respect to the bolster to effect setting movements of the damper plate.

5. In a damper, a damper frame, a bolster 10 at one end thereof, a damper plate pivotally mounted in said frame, means carried by the damper plate and engaging the upper surface of the bolster for supporting a portion of the weight of the damper plate, and operating means connected to the pivot of the damper plate for overcoming the frictional resistance of the first named means with respect to the bolster to effect setting movements of the damper plate.

20 6. In a damper, the combination with a damper frame, and a damper plate having pivotal connection to said frame, of a bolster element in fixed relation with respect to the frame, said bolster having a curved upper

surface disposed in approximately concentric relations with respect to said pivotal connection, and means carried by the damper plate and arranged to bear upon the curved surface of said bolster whereby the latter serves to retain the damper plate in adjusted 25 positions.

7. A damper comprising a frame, a bolster element protruding upwardly from one end thereof, said bolster having an arcuate upper surface, a damper plate pivotally connected to an end of said frame below the bolster and approximately axially of the arc of the upper surface thereof, and means carried by the damper plate and adapted to bear upon the said surface to cooperate with the pivotal connection of the damper plate for supporting the entire weight of the latter in different positions of the same.

Signed at Seattle, Washington, this 23rd day of February 1924.

GLENN A. MORRELL.
